REFUSE DISPOSAL

Frank S. Simpson, Alton, Ill., assignor to Illinois Stocker Company, Alton, Ill., a corporation of Delaware
Filed Oct. 26, 1964, Ser. No. 406,517
5 Claims. (Cl. 110—7)

This invention relates generally to refuse disposal, and in particular concerns an improvement upon the method and apparatus disclosed in my copending application Ser. No. 301,401, filed Aug. 12, 1963, now Patent No. 3,289,617, of which this application is a continuation-in-part.

The above-mentioned copending application discloses a method and apparatus for agitating the burning bed of refuse on the traveling grate of an incinerator of the municipal type. This is accomplished by the injection of air, or other gas, through the grate, and under pressure sufficient to locally lift, expand and fluff matted, wet, and otherwise compacted, components of the refuse bed. Structurally speaking, the disclosure of said copending application added to the conventional structure, for such an incinerator, means for injecting gas under relatively high pressure upward through the grate beneath the bed of burning refuse. The magnitude of the pressure on the injected air was intended to be substantially in excess of that theretofore applied to force a draft through the openings in the grate, so that the pressure is sufficient to overcome, or locally lift, the dead weight of the affected increments of refuse on the traveling grate. Said application pointed out that suitable pressure on the injected air, or other gas, to accomplish the desired agitation might be between twelve and thirty inches of water—the deeper the bed of refuse, the higher the required pressure on the injected air. The copending application pointed out that the higher pressure was preferred because, consistent with the economy of operation, it does no harm, but does permit of intermittent operation, and hence conserves the energy consumed in so injecting the air when the burning refuse bed does not require it.

It has now been discovered, however, that there are 40 certain sets of conditions under which the maintenance of the high pressure on the injected gas is undesirable; and intermittent operation may be impractical because between the time the need for the high pressure subsides and the time the source of high pressure can be de-activated, there is a hiatus during which lighter material following in succession behind the heavy material is unduly agitated.

Accordingly, it is an object of this invention to so control the flow of high pressure air, or other agitating gas, so that when the need for it at a given locus subsides, it is automatically discontinued at that locus. And when the need for agitation occurs, such need is automatically sensed, and the pressure on the agitating gas increased.

Generally stated, the invention contemplates the provision, in each of the tuyeres which delivers the agitating gas at a given locus, of means responsive to excess pressure at that locus to increase the same; and responsive to a sudden decrease in pressure at that locus to further decrease the same. In the operation of an incinerator of the character aforesaid, when an increment of refuse which requires agitation passes over the orifice from such a tuyere, the pressure adjacent that orifice increases because the air therein cannot escape through the orifice. When this occurs, the present invention contemplates that the pressure at that orifice be automatically increased to a value sufficient to agitate, loosen, and permit the flow of air therethrough. Upon such loosening, the pressure adjacent that orifice suddenly declines because the air therein finds escape through the agitated refuse; and when this occurs, the sudden drop in pressure adjacent the orifice activates a further drop to the operating pressure level.

2

The invention further contemplates the provision of a separate compartment about each of the throats which delivers the air (to support combustion and/or to agitate the bed of refuse) beneath a section of traveling grate. In a conventional incinerator of the type referred to, and as shown in the aforesaid copending application, a series of such throats, usually from three to six in number, is aligned crosswise to the direction of travel of the grate, and such series is repeated from increment to increment along the length of the burden-bearing reach of the traveling grate for such distance as it is desired to force combustion. Thus, in accordance with the present invention, the separate compartmentation of orifices in each series extending crosswise with reference to the length of the traveling grate permits the regulation of pressure at one orifice, independently of the pressure at another orifice in the same series, and independently of all the orifices in any other series.

More specifically, the invention contemplates that each orifice compartment be connected with a source of high pressure air, or other gas, which is maintained more or less constantly at the highest pressure which may be needed, e.g., a pressure of twelve to thirty inches of water; and that each such compartment be provided with means 20 for controlling the volume of air, or other gas, flowing from the source into that particular compartment, depending upon whether the momentary over-burden at that compartment requires agitation or not. Moreover, the invention envisions that the control means provide, constantly into each compartment, at least a sufficient volume of gas to maintain the desired combustion rate.

For a more specific disclosure of an embodiment of the method and apparatus contemplated by the present invention, reference may be had to said copending application 35 wherein a series of orifice plates 15, each having a central opening 16 communicating with the upper end of a throat 14, is arranged crosswise of a traveling grate incinerator at a number of stations lengthwise thereof. At least one of these stations, the series of throats 14 is supplied with air under sufficient pressure to lift and agitate a compacted over-burden on the traveling grate. The high pressure air is applied to each of the throats in that series through a wind box 7. A permanently open hole in the upper side of the wind box 7 constantly admits the high pressure air to the respective throats 14, irrespective of whether the momentary over-burden at that throat requires agitation. In substitution for the part of the incinerator of the copending application just referred to, the structure shown in the accompanying drawings may be utilized to carry out the concepts of the present invention. In the accompanying drawings:

FIGURE 1 is a top plan view of a series of orifice plates constructed, arranged and controlled in accordance with the present invention, it being understood that the traveling grate (not shown) moves across the series of orifice plates in the direction from top to bottom or from bottom to top, as desired;

FIGURE 2 is a sectional view taken along line 2—2 of FIGURE 1, and schematically showing the location 55 of the traveling grate; and

FIGURE 3 is a sectional view taken along line 3—3 of FIGURE 2, and typifies the structure and arrangement of parts beneath the respective orifice plates.

In the form shown in the drawings, the apparatus for carrying out the present invention involves a blower, or like source of high pressure gas 11 connected through a duct 12 to a tuyere 13. The tuyere 13 is controllably vented into separate compartments 14 beneath each of the several orifice plates 15, of which there are five in series arranged crosswise the direction of travel of the grate as shown in FIGURES 1 and 2.

Each compartment 14 is separated from its neighbor by a wall 50 extending vertically downward from the conventional carry bars 51 to a suitable compartment floor shown in the form of a door 52. Between the carry bars 51, the orifice plates 15 are arranged so as to bridge the space between supporting I-beams 53, all in accordance with the usual practice. Each of the compartments 14 has an end wall 54 extending downwardly from one of I-beams 53 to floor 52; each of such compartments also has an opposite end wall 55 which separates it from tuyere 13, and which, except for the devices now to be described, completes the enclosure of compartment 14. Wall 55 is provided with an opening 56, through which air under pressure may pass from tuyere 13 into compartment 14. A damper 57, hinged for rotation about axis 58, is provided for controlling the volume of air passing from tuyere 13 into compartment 14 at any increment of time. In the full line position shown in the drawings, the damper 57 is closed, but it will be observed that the damper is deliberately made loose of fit within opening 56, so that regardless of the fact that the damper may be in its closed position, some air may nevertheless pass from tuyere 13 into each of the compartments 14. That is to say, that, regardless of other conditions, enough air is always passed through opening 56 to sustain the combustion of the over-burden on the traveling grate.

Also, in wall 55, there is provided a damper operator or control of the character which senses the prevalence of excess pressure in compartment 14, and responds by opening damper 57 so as to increase the pressure therein; or conversely, when the pressure in compartment 14 suddenly drops, the control operates the damper in the direction which tends to further reduce that pressure.

In the embodiment shown, the aforesaid damper operator or control takes the form of a differential area piston cylinder combination, with the larger piston 59 in the larger cylinder 60 exposed to the pressure in compartment 14, while the smaller piston 61 in the smaller cylinder 62 is exposed to the pressure in tuyere 13. Under normal operating conditions, i.e., where the overburden above orifice plate 15 is loose and not obstructing the flow of air therethrough, the pressure in compartment 14 will be low (e.g., 3 inches of water) in comparison with the pressure (e.g., 18-20 inches) in tuyere 13, and the damper 57 will be closed, or substantially so. When the over-burden above a given plate 15 is too tight or compacted to permit the air to flow therethrough in the normal way, the pressure in the associated compartment 14 rises (e.g., to 14 inches). As the pressure in compartment 14 rises, its action on the larger piston 59 results in a force which exceeds the opposite force resulting from the exertion of the higher pressure in tuyere 13 upon the smaller piston 61—and consequently moves the piston combination 59-61 rightwardly, as shown in FIGURE 3. Such movement to the right is communicated by rod 63 to lever 64, which is fulcrumed at 65, so as to move the lever in the clockwise direction (as shown in FIGURE 3), and so as to force link 66 leftwardly. The link 66 is pivotally connected at 67 with damper 57. Consequently, the movement of the piston combination 59-61 to the right rotates damper 57 in the counterclockwise direction (as shown in FIGURE 3). When the damper 57 has been thus opened, a greater volume of the high pressure air in tuyere 13 flows through orifice 56 than theretofore, thereby increasing the pressure in compartment 14 until the overburden is agitated and released sufficiently to permit the escape of air therethrough, at which time the pressure in compartment 14 suddenly drops.

In order to prevent the back side of piston 59 from being subjected to the relatively high pressure in tuyere 13, the back side of cylinder 60 is permanently enclosed by a flange 68 on cylinder 62; and in order to avoid the retarding influence of fluid entrapped in the space between piston 59 and flange 68, that space is vented to

atmosphere through a pipe 69 and header 70. The header 70 preferably communicates with vent pipes like 69 for each of the several compartments 14.

When the pressure in any one of the compartments 14 thus drops the force tending to move its piston combination 59-61 to the right is reduced below the force tending to move its piston combination to the left in response to the constantly higher pressure in tuyere 13. Consequently, the damper 57 of that compartment is thereby moved toward its closed position, thus reducing the volume of high pressure air passing through orifice 56 to its normal value, and maintaining it in that position until the pressure in that compartment again becomes abnormally high in response to obstruction of its escape through the over-burden.

It will be understood that as many of the compartments 14 as desired (preferably all of them at a given station lengthwise of the incinerator) are equipped with the automatic pressure regulation described.

From the foregoing description, those skilled in the art should understand the construction and operation of the invention, and realize that the control means, whether in the form shown or in any other form, which is responsive to excess pressure in compartment 14 to increase that pressure and is responsive to sudden drops of pressure in compartment 14 to further drop that pressure, provides a control which is automatically responsive to the character of over-burden passing over the given compartment. As aforesaid, an individual such control is provided for each compartment, under each orifice plate in the series, of an incinerator which is equipped with a high gas pressure agitation means.

While one form of the invention has been disclosed in detail, it is to be distinctly understood that the invention is not limited to the form shown, but that, on the contrary, those skilled in the art will be expected, in the exercise of the skills of their callings, to provide other forms of controls which function to produce the same result, all without departing from the spirit of the invention, or the scope of the appended claims.

Having thus described the invention, what is claimed and desired to be secured by Letters Patent is:

1. In a refuse incinerator of the type having a traveling grate for sustaining and moving a bed of burning refuse, said grate having apertures therethrough, the improvement which comprises a series of separate compartments extending crosswise of the direction of travel of said grate and below said grate for directing air through those of said apertures disposed above the individual compartments respectively, a source of air under pressure of at least twelve inches of water, said source communicating with all compartments of the series, each compartment of the series having a damper controlling its communication with said source, separate means in each compartment responsive to changes in pressure in that compartment, said means moving in one direction when the compartment pressure increases and moving in the opposite direction when the compartment pressure decreases, and means responsive to movement of said pressure responsive means for actuating the damper for that compartment to open the damper when the pressure in that compartment increases and to close it when the pressure in that compartment decreases.

2. The combination of claim 1 wherein said damper when closed admits the flow of some air from said source to said compartment.

3. A refuse incinerator of the type having a traveling grate for sustaining and moving a bed of burning refuse, said grate having apertures therethrough, means for forcing air upwardly through said apertures at relatively low pressure to support combustion, and means responsive to abnormal obstruction of the flow of air through said apertures to increase the pressure on the air delivered to said apertures to an extent sufficient to agitate the bed of refuse overlying said apertures.

4. In the art of incinerating refuse on an apertured grate the process comprising, providing a plenum chamber having an open communication with the lower side of the apertured grate, supplying said plenum chamber with air under pressure normally sufficient to force it through said apertures, and, when the pressure in said plenum chamber exceeds normal, increasing the pressure therein.

5. In a refuse incinerator of the type having a traveling grate for sustaining and moving a bed of burning refuse, said grate having apertures therethrough, compartments below said grate for directing air through those of said apertures disposed above it, and a source of pressurized air communicating with said compartments, the improvement which comprises, said compartment having a 10
15
15
damper controlling its communication with said source, a

differential area piston-cylinder arranged with the piston of larger area exposed to pressure within said compartment and with its piston of smaller area exposed to pressure of said source, and means for converting motion of said differential area piston-cylinder into motion of said damper to open said damper when the compartment pressure increases and to close said damper when the compartment pressure decreases.
